Primary Examiner — Janice Hallmark*Assistant Examiner* — Adedoyin Taiwo Odeyale(74) *Attorney, Agent, or Firm* — Patterson Thuente, P.A.(57) **CLAIM**

We claim the ornamental design for a desalination pod, as shown and described.

DESCRIPTION

FIG. 1 is a perspective view of a desalination pod showing the claimed design;

FIG. 2 is a front view thereof;

FIG. 3 is a right side view thereof;

FIG. 4 is a left side view thereof;

FIG. 5 is a rear view thereof;

FIG. 6 is a top view thereof; and,

FIG. 7 is a bottom view thereof.

The broken lines in the drawings illustrate portions of the desalination pod that form no part of the claimed design.
